UNITED STATES PATENT OFFICE.

ELMO M. CHANDLER, OF TORONTO, ONTARIO, CANADA.

STRUT FOR AUTOMATIC SPRINKLERS.

Application filed February 26, 1921. Serial No. 448,201.

To all whom it may concern:

Be it known that I, ELMO M. CHANDLER, a citizen of the United States, and resident of the city of Toronto, in the Province of 5 Ontario and Dominion of Canada, have invented certain new and useful Improvements in Struts for Automatic Sprinklers, of which the following is a full, clear, and exact description.

- 10 This invention relates to improvements in automatic sprinklers, and the object of the invention is to provide a device which may be easily and cheaply manufactured and which will be quick and certain in operation.
- 15 The device consists briefly of a pair of hingedly related overlapping strut members adapted to be held in compression in a sprinkler, and a key hingedly connected to one of the members and overlapping the 20 other member to hold the same in position when all three are soldered together.

In the drawings which illustrate the invention;—

- Fig. 1 is a front elevation.
25 Fig. 2 is a vertical section on the line 2—2, Figure 1.

Referring more particularly to the drawings, 11 and 12 designate a pair of strut members hingedly connected at 13 by the 30 tail 14 of the member 12 pivotally engaging in a recess 15 in the head 16 of the member 11, the point of engagement being located out of the axial line of the strut containing the load bearing points 17. The tail 18 of the member 11 lies alongside of and in engagement with the tail 14 and on the opposite side thereof from the strut axis. A key 19 is provided having a tail portion 20 lying alongside of and in engagement with 35 the tail 18, said tail 20 being reduced at its free end to provide a solder holding shoulder 21. The free end of the key tail is housed under an overhanging or projecting portion 22 of the member 11, the said portion being designed to hold an accumulation 40 of solder, as indicated at 23. The lower portion of the key is apertured at 24 for the passage therethrough of the body of the strut member 12 and the apertured portion 45 is disposed at an angle to the tail portion 20. The member 12 is provided with a surface 25 normal to the plane of the apertured key portion, against which the key bears. In order to hold the key against slipping off 50 its bearing surface 25, the member 12 is provided with lips 26 and 27 above and below

the key seat 25 and disposed at such angles thereto that the key will be free to rock about the bearing line 28 or, if any impedance to such rocking is presented, the key 60 will be free to slide partially or wholly over the lip 27 during its releasing movement. The member 12 is a loose fit in the key but, to ensure proper action and to guard against the possibility of corrosion uniting the parts, 65 the member 12 is reduced in width, as shown at 29, the reductions commencing at a shoulder 30 located in the thickness of the apertured portion of the key when the strut is assembled, as clearly shown in Figure 2. 70

The operation of the device is extremely simple. The parts being assembled and the key held by solder, as indicated at 23, the strut is gripped at its load points 17 and placed in compression. The pivotal or hinge 75 point 13 between the members being out of the load line, the two parts tend to swing about one another at the point 13 but this movement is restrained by the key overlying the tail 18 and holding the same against the 80 tail 14. The apertured portion of the key is so disposed as to lie almost in the plane of movement of the end of the tail 18, so that the metal of the key is almost entirely in tension. The tendency of the tail 18 is to 85 swing the tail of the key away from the axis, the end of the tail 18 being rounded at 31 to facilitate such movement. The body of solder between the end of the key tail and the lip 22 normally holds the key against 90 movement, so that the strut remains rigid. When the solder 23 is softened by heat, it allows the key tail to fly outwardly, releasing the tail 18 and permitting the strut to 95 collapse. The members of the strut form in themselves a toggle, the tail 18 of the key being a lever to magnify movement of the hinge joint of the toggle and transmit the same to the key. The key tail constitutes a second lever further magnifying toggle 100 movement. The result is that an almost imperceptible shortening of the strut between its load points is transformed to a very considerable movement at the free end of the key tail. Conversely, slight movements of 105 the key tail which occur as the solder is softening are so reduced that they do not permit shortening of the strut sufficiently to cause any leakage of the sprinkler valve. Shortening of the strut sufficient to cause 110 any leakage or water flow is possible only after the key end has swung out from under

the lip 22, that is to say, after the solder has softened sufficiently to entirely release the key.

Having thus described my invention, what I claim is;

1. A strut for sprinklers and the like, comprising a pair of overlapping hingedly connected members, and a key apertured for the passage of one of the members and hingedly related at one end to the member passing through it on one side of the strut axis and overlying at its opposite end the other strut member on the opposite side of the strut axis.
- 15 2. A collapsible strut for sprinklers and the like comprising a pair of hingedly related overlapping strut members, a key including a tail overlapping the overlapping portions of said members, and a laterally directed portion apertured for the passage of

one of the strut members and forming a link embracing the strut member and hingedly connecting the key thereto.

3. A structure according to claim 2, in which the member passing through the key 25 is reduced in width in the portion passing through the key and in the path of the key to provide clearance.

4. A device according to claim 2, in which the apertured portion of the key is disposed 30 to be in tension between the members of the strut.

5. A device according to claim 2, in which the strut member passing through the key includes a key seat portion, and lips flanking the seat portion arranged to releasably hold a key on the seat portion.

In witness whereof, I have hereunto set my hand.

ELMO M. CHANDLER.
